UNITED STATES PATENT OFFICE.

WALTER J. GADSBY, OF BOSTON, MASSACHUSETTS, ASSIGNOR TO ROXBURY
CARPET COMPANY, OF SAME PLACE.

DESIGN FOR CARPET.

SPECIFICATION forming part of Design No. 12,191, dated March 22, 1881.

Application filed February 14, 1881. Term of patent 3½ years.

To all whom it may concern:

Be it known that I, WALTER J. GADSBY, a subject of the Queen of Great Britain, residing at Boston, in the county of Suffolk and 5 State of Massachusetts, have invented a new and original Design for Carpets, of which the following is a specification.

The nature of my design is shown in the accompanying photographic illustration.

10 The design is composed of an aggregation of figures, A B C D E, the figures A being octagonal, the figures B being rectangular and arranged in rectangular order around the figures A, the figures D being dodecagonal, with 15 eight salient and four re-entrant angles, the figures C being substantially rectangular, (each

having a scalloped edge,) and arranged in rectangular order around the figures A and D, and the figures E being rhomb-shaped and arranged around the figures D.

20

I claim—

The design for carpets, substantially as shown and described.

In testimony whereof I have signed my name to this specification, in the presence of two subscribing witnesses, this 12th day of February, A. D. 1881.

WALTER J. GADSBY.
